UNITED STATES PATENT OFFICE.

GODFREY MARSHALL, OF INDIANA, PENNSYLVANIA.

IMPROVEMENT IN HARNESS-SADDLES.

Specification forming part of Letters Patent No. **70,589**, dated November 5, 1867.

To all whom it may concern:

Be it known that I, GODFREY MARSHALL, of the city and county of Indiana, and State of Pennsylvania, have invented a new and useful Improvement in Saddles; and I do hereby declare that the following is a full, clear, and exact description thereof, which will enable others skilled in the art to make and use the same, reference being had to the accompanying drawings, and to the letters of reference marked thereon.

The present invention relates to the saddles of harnesses more particularly; and consists in making the top or frame to the saddle in one piece, having a raised flange or lip around its sides or edges, upon its back or under side, and between such lips placing the cushion or pad, made of the proper shape, and provided with screw-nuts in proper position for receiving the terret-rings, screw-shanks, and other screw-bolts, by means of which the pad is secured to the frame, at the same time also fastening the saddle-straps.

In the accompanying plate of drawings my improvement in saddles for harnesses is illustrated, Figure 1 being a central section through a harness-saddle complete, and when made according to the present invention; Fig. 2, a

view of the cushion or pad; Fig. 3, a cross-section of the saddle-frame.

A in the drawings represents the top or frame to the harness-saddle, made of one piece of metal or other suitable material, and provided with a lip or flange, B, along its sides or edges C, between which the cushion or pad D is placed, made of proper size and shape therefor. This pad is provided with screw-nuts E at the proper points to receive the screw-shanks to the terret-rings, and also the screw-bolts G, by means of which the pad is fastened to the frame or top.

F, saddle-straps, fastened to the saddle-frame by the screws G, that are used for fastening the pad to the frame.

Having thus described my invention, I claim as new and desire to secure by Letters Patent—

A harness-saddle constructed with its cushion or pad, substantially as and for the purpose described.

The above specification of my invention signed by me this day of , 1867.

GODFREY MARSHALL.
